UNITED STATES PATENT OFFICE.

ADDISON J. LYON, OF MOUNT VERNON, NEW YORK.

KEY-FASTENER.

SPECIFICATION forming part of Letters Patent No. 478,448, dated July 5, 1892.

Application filed October 29, 1891. Serial No. 410,237. (No model.)

To all whom it may concern:

Be it known that I, ADDISON J. LYON, a citizen of the United States, residing at Mount Vernon, county of Westchester, and State of 5 New York, have invented new and useful Improvements in Guards for Locks and Keys, of which the following is a specification.

This invention relates to guards for locks and keys; and it consists in novel features of 10 construction, which are fully described in the following specification and claim, reference being had to the accompanying drawings, in which—

Figure 1 is a front view of my improved 15 guard applied to a lock, the barrel of the key being shown in cross-section. Fig. 2 is also a front view thereof when turned to one side on its pivot, the key not being seen in this view. Fig. 3 is a vertical section on the line xx of 20 Fig. 1.

One of the objects of my invention is the security of keys, which are often lost by reason of their withdrawal from the locks to which they belong.

25 Another object is to prevent persons from opening a lock whose key is left in the lock by seizing the key from without.

In carrying out my invention I make a guard A from sheet metal or other suitable material 30 which possesses a good degree of elasticity and fasten it by a pivotal screw B to the face or face-plate C of a lock in such a manner that the guard can be turned on its pivot in one or both directions.

35 In applying my invention to the locks of houses or stores or dwellings I place it generally on the inside faces of the doors; but I do not limit myself to its application at any particular place, as it can be adapted to locks 40 of various descriptions.

In the example of my invention here shown the guard A is placed on the inside of a door on the face-plate C of the lock which is to be protected, to which it is fastened by a screw 45 B, which may be the same screw that fastens the lower part of the face-plate C to the door or to the lock-casing. The head of the screw B is so constructed that it will allow the guard A to be turned toward the right hand or left 50 hand without starting the screw and without turning the screw out of the door or the face-

plate; but it is requisite that the head of the screw shall bear on the guard in such a manner as to press the guard against the face-plate sufficiently close to produce frictional 55 contact between them, so that the guard will remain in any position to which it is turned.

The guard A is preferably made of elastic material and its natural elasticity is increased, if desired, by bending it in the proper direction, as is indicated at D in the drawings.

The guard A is constructed and arranged in such a manner that the point on which its pivot turns is in line with the keyhole E of the lock and its length beyond or above its 65 pivotal point is such that its free end extends over the lower part of the keyhole and as far as to that part of the keyhole which contains the barrel F of the key, so that when the guard A has been moved to its vertical position, as 70 in Figs. 1 and 3, its upper edge G will extend up to the barrel of the key, so that it will swing beneath it, but so as to clear it.

The under side of the guard A near its free end is provided with a nipple H, which when 75 the guard is in its vertical position projects into the keyhole, from which position it is moved toward either the right hand or the left hand by hand, for which purpose the guard A is provided with ears I I on its sides opposite the nipple, so that one taking hold of the ears can by that means swing the guard in either direction and slide the nipple out of the keyhole. When the nipple is out of the keyhole, it rests on the face-plate C and is 85 held stationary by the spring-like action of the guard pressing on the face-plate until again moved by hand.

My improved lock and key guard can be made of any suitable material and to suit any 90 form of lock which is provided with keyholes and any form of key which is provided with a barrel projecting into a keyhole.

In applying my improvement to use the free end of the guard A is turned to one side of the 95 keyhole, as shown in Fig. 2, and the key is then inserted into the keyhole and the guard pushed to the position shown in Figs. 1 and 3, in which position it prevents the key from being pushed or pulled outward or inward, as 100 the guard A is interposed to prevent the bit J from passing through the keyhole in an in-

ward direction and the guard is also interposed so as to prevent the ring K of the key from being pulled outward through the keyhole or into the same.

5 What I claim as new, and desire to secure by Letters Patent, is—

In guards for locks and keys, the elastic guard A, provided with a nipple H and ear-pieces I and pivoted to a door or lock below the keyhole, the free end of the guard being adapted to swing over the keyhole below the

barrel of the key, the nipple H being adapted to fall into the keyhole and interlock the guard therewith, substantially as shown and described.

In testimony whereof I have hereunto set my hand in the presence of two subscribing witnesses.

15 ADDISON J. LYON.
